FLOCKED FABRIC OR SIMILAR ARTICLE

Victor Amorino, West New York, N. J.

Application June 24, 1955, Serial No. 36,659

Term of patent 3½ years

(Cl. D47—6)

The figure is a plan view of a flocked fabric or similar article showing my new design; a unit of design consists of the design shown commencing with the left hand border of the drawing and extending to the commencement of the third clef sign; the third clef indicates the commencement of repetition in the design; it is a duplicate of the first clef; the design repeats the first two clefs in regular succession.

I claim:

The ornamental design for a flocked fabric or similar article, as shown and described.
